CLAIM

The ornamental design for a toy shield, as shown and described.

DESCRIPTION

FIG. 1 is a front, top perspective view of a toy shield, showing our new design;

FIG. 2 is a rear, bottom perspective view thereof;

FIG. 3 is a front, bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is an enlarged perspective view of detail "10" identified in FIG. 2;

FIG. 11 is another perspective view of FIG. 1, shown in an alternative position; and,

FIG. 12 is another perspective view of FIG. 1, shown in an alternative position.

The dashed lines in the figures illustrate portions of the toy shield that form no part of the claimed design. The dash dot dash lines in FIGS. 2 and 10 are for the purpose of illustrating the enlarged view indicators and form no part of the claimed design.

1 Claim, 12 Drawing Sheets
